(57) **CLAIM**

The ornamental design for a meditation headset, as shown and described.

DESCRIPTION

FIG. 1 is a perspective view of a meditation headset showing my new design;

FIG. 2 is a front view of the meditation headset;

FIG. 3 is a rear view of the meditation headset;

FIG. 4 is a left side view of the meditation headset;

FIG. 5 is a right side view of the meditation headset;

FIG. 6 is a top view of the meditation headset; and,

FIG. 7 is a bottom view of the meditation headset.

The broken lines in the drawings showing elements of the meditation headset represent unclaimed portions of the meditation headset and form no part of the claimed design.

1 Claim, 6 Drawing Sheets
